UNITED STATES PATENT OFFICE.

ARNOLD LOUIS CHEVALLIER, OF LONDON, ENGLAND.

AUTOMATIC FIREARM.

Application filed December 12, 1918. Serial No. 136,531.

(GRANTED UNDER THE PROVISIONS OF THE ACT OF MARCH 3, 1921, 41 STAT. L., 1313.)

To all whom it may concern:

Be it known that I, ARNOLD LOUIS CHEVALLIER, a subject of the King of Great Britain, residing at 6 Knaresborough Place, 5 Cromwell Road, London, England, have invented new and useful Improvements in Automatic Firearms (for which I have filed applications in Great Britain, Apr. 20, 1915, and Nov. 19, 1915), of which the following 10 is a specification.

This invention relates to improvements in automatic small arms of the type which comprises an inertia weight within which are an unlocking spring and a firing spring 15 so arranged that during the rearward movement of the barrel on recoil these two springs are compressed and the subsequent expansion of the unlocking spring causes first a rotation of the bolt to unlock and then 20 the rearward movement of the bolt, weight and bolt carrier, while the expansion of the firing spring is prevented by a sear engaging a bent on the firing pin, the forward movement of the weight and bolt being effected by a closing spring or springs. 25

The object of the present invention is to render the automatic action more certain and to effect various other improvements in the weapon.

The invention is illustrated by the accompanying drawings, Figures 1 and 1^a of which are a longitudinal section of a weapon made in accordance therewith; Figure 1^b is a side view of the bolt; Figures 2 and 3 are transverse sections on lines 2—2 and 3—3 respectively; Figure 4 shows a detail; Figures 5, 5^a and 5^b are a right hand elevation parts being in section and Figures 6, 6^a and 6^b a plan of a weapon similar in its 30 action to that shown in Figures 1 and 1^a but fitted with a jacket to prevent overheating. Figure 7 is a rear view of the weight and Figure 8 a transverse section through the muzzle and jacket. Figures 9 and 9^a are a left hand elevation of the shoe and weight; Figures 10 and 10^a are a plan of the shoe; Figure 11 is a front view of the weight and Figures 12 and 13 are sections on lines 40

12—12 and 13—13 of Figures 9^a and 10 respectively. Figure 14 is a longitudinal section and Figure 15 a plan of the raceway. Figure 16 is a longitudinal section of the raceway showing the closing spring. Figure 17 is a side elevation of the raceway and weight. Figure 18 is a section through the boss on line 18—18 of Figure 14. Figure 19 is a section on the line 19—19 of Figure 17. Figures 20, 21, 22 and 23 are sections on the lines 20—20, 21—21, 22—22, 23—23, of Figure 14, and Figure 24 is a section on the line 24—24 of Figure 22. Figures 25 and 26 are a left hand elevation and a front view of the bolt carrier.

1 is the shoe, 2 the barrel, 3 the boss, 4 the raceway and 5 the weight.

The barrel is supported by two rings or tubes 6, 7, of which 6 is split and is carried by a block 8 which fits into the front of the shoe, being secured by a screw 9. Into the block 8 screws a rod 10 which carries at its rear end a strap 11 embracing and clamping the ring 6. The rings 6, 7, are kept at the correct distance apart by a sleeve 12 surrounding the rod 10. The ring 7, which carries the foresight 13, is surrounded and strengthened by a strap 14 into which the enlarged front end of the rod 10 fits and which is prolonged rearward to form the bayonet attachment.

The barrel is screwed with a left handed thread (so that the action of the bullet on the rifling may tend to screw the barrel tighter) into the boss 3 which is formed in one with the raceway 4. On the underside of the latter is a feather 15 in the shape of an inverted T. This is of such a length that in assembling it can enter the opening 16 in the shoe through which the cartridges rise from the magazine 17. The feather engages grooves 18 cut in the shoe. The boss also has upon it lateral ribs 19 which engage grooves 20 near the front of the shoe.

On the underside of the boss is a lug 21 which enters through a slot 22 (see Figure 10^a) a cylindrical space 23 in the shoe and

bears against a helical run-out spring 24 surrounding a pin 25 screwed into the shoe.

The barrel and raceway are thus capable of recoiling relatively to the shoe against 5 the run-out spring 24. In order to stop the automatic action and convert the weapon into a single loader, I provide a plunger 26 which can be moved transversely through grooves in the boss and shoe. This plunger 10 has in it a groove 27 so that when it is in the position shown in Figure 2, the boss can recoil, but when it is pushed transversely into its other position in which it will be held by a spring 28 engaging a nick, movement between the recoiling and non-recoiling parts is prevented and the weapon is no longer capable of automatic action.

In the space 23 and in front of the lug 21 is a cushioning spring 29 adapted to prevent 20 the recoiling part from hammering against the non-recoiling part when it is returned by the run-out spring. 30 is a piston mounted on a rod 31 and interposed between the lug and the spring 29.

25 32 is the bolt carried by the tubular bolt carrier 33 which surrounds the two springs 34, 35. The action of the weight, the bolt, the bolt carrier and the springs is very similar to that of the corresponding parts as 30 described in British specification No. 16175 of 1912 except that the helical lugs and grooves are situated between the bolt and the bolt carrier. Normally the weight is locked to the non-recoiling part i. e. the 35 shoe, by a lever 40 mounted on the right of the weapon on a horizontal pivot 41 and having a lug 42 engaging a shoulder 43 on the weight.

On recoil a stud 44 on the boss comes 40 against an incline 45 on the lever and turns it down withdrawing the lug 42 from behind the shoulder 43 so that the weight is freed. 46 is a spring which presses the lever upward into its operative position 45 and the movement of the lever is limited by a stud 47. In order that it may be possible readily to release the weight when desired, the lever is prolonged upwards and carries a thumbpiece 48. On firing therefore 50 the weight remains stationary and the barrel, bolt carrier and bolt recoil relatively to the weight, compressing the springs 34 and 35; the spring 35 is, as will be described later, prevented from expanding, but when 55 44 comes against incline 45, the weight is freed from the shoe and the spring 34 expands driving the weight rearward relatively to the bolt carrier. This is the only function of the spring 34. The weight and 60 carrier then recoil together and move rearward away from the barrel and boss which are now checked by the run-out spring: the helical-lugs 321 (see Figure 1^b) and grooves now rotate the bolt for one sixteenth part of a revolution to unlock and

the bolt does not start recoiling away from the boss until the carrier has moved away from it about half an inch. It then moves rearward with the carrier and is prevented from turning by the engagement of a tooth 70 36 formed upon it with a groove 37 in the raceway. At the end of the forward movement of the bolt this tooth leaves the end of the groove and the bolt is turned to lock by the momentum of the weight and carrier. 75

The movement of the bolt carrier relative to the weight is limited by a stud 38 screwed into the weight and entering a slot in the bolt carrier. It will be seen that the entire movement of the barrel and raceway 80 relatively to the shoe is greater than the movement of the barrel, bolt carrier and bolt relative to the weight before the unlocking but is less than twice that movement. Rotation of the carrier within the weight is prevented by a guide rod 39 which projects rearward from the front of the carrier and enters a longitudinal hole bored in the weight.

The closing spring 49 is contained in a 85 tubular casing 50 as shown in Figures 15 and 16. In front of the spring is a plug 51 having on it a tooth 52 which extends out through a slot 53 in the casing 50 and engages an arm 54 on the bolt carrier. The 90 closing spring is preferably made in two parts with a double thimble 55 between them.

Or I may connect the carrier to the closing spring as shown in Figures 17, 19, 25 100 and 26 by a lever 56 pivoted on a longitudinal pivot 57 in the carrier and having an arm 58 passing through a slot in the raceway and engaging an annular groove 59 in a plug 60 at the front of the spring. The 105 lever is normally kept in engagement by a spring 61 against which it can be turned by hand when it is desired to disconnect the carrier from the spring. The operation is as follows:—On discharge the weight being locked to the shoe by parts 42 and 43 the barrel and raceway recoil against spring 24 until stopped by pin 25. During this part of the recoil spring 34 is compressed by the bolt carrier and spring 35 is compressed by the firing pin; stud 44 then comes against part 45 of lever 40 which frees weight 5. Spring 34 is therefore free to expand, driving weight 5 and carrier 33 rearwardly slightly relative to bolt and barrel. The bolt is therefore turned owing to the engagement of its helical lugs 321 with the corresponding grooves in the interior of carrier 33 and is therefore unlocked from the boss 3. The weight, its springs, the bolt carrier and bolt are therefore free to move rearward, which they do, compressing spring 49. As this spring expands again it moves the bolt carrier, bolt and weight forward again and the carrier thrusts 125 130

the bolt into the barrel and locks it, and the piece is ready to fire.

In Figure 6 is shown a supplementary buffer 62 and run-out spring 63 lying in a hole in the raceway and bearing against a stop pillar 64 which carries the backsight.

The rearward movement of the weight is normally limited by a pair of stops 65 carried by a spring blade 66. These stops lie in the path of shoulders 67 on the side walls of the weight. Should it be desired to withdraw the weight beyond its normal rearmost position, the blade can be bent down by pressing on the stops with the fingers.

15 The motion of the weight in front of its normal position is prevented by a stud 68 on the shoe (see Figures 9 and 10).

The operating lever 69 surrounds the rear part of the weight and has upon it toes 70 adapted to engage slots 71 at the rear of the raceway to retain the anti-recoiling part, when the lever is turned into the correct position, at the rear of the hand travel and to engage slots 72 in the middle of the raceway when the lever is turned right over to the dotted position of Figure 6. In this position the weapon is safe as the cam surface of the lever 69 then lies in the path of the tail 73 of the firing pin 74 and prevents it moving forward to fire.

The pin 74 passes through the bolt and through the rear part of the weight and its rear end is flat at the sides (see Figure 3) to prevent it from turning on its axis.

35 A bent is formed in it by removing a portion of it and at this bent it is surrounded by a ring 75 pressed downwards by a spring 76 in the top of the weight. When the pin 74 moves to the rear at the commencement 40 of recoil, that is, before the weight partakes in the recoil, the ring 75 drops into the position in which it is shown in Figures 1 and 3 and prevents the firing spring from expanding, that is, keeps the weapon cocked.

45 77 is the trigger pivoted on a transverse axis 78 and having a forwardly projecting arm 79, the front of which carries a pivoted nose 80 pressed against a stop 81 by a spring 82. This nose normally rests against 50 a shoulder 83 at the rear of a lever 84 pivoted on a transverse stud 85; the front of this lever lies between the jaws of a piece 86 normally held down by a spring 87. Between the piece 86 and the ring 75 is a 55 plunger 88. When the trigger is pulled the nose 80 rocks the lever 84 which raises the plunger 88 and this lifts the ring 75, thus allowing the pin 74 to fly forward and fire. The nose 80 slips off the end of the lever

60 84 which is restored to the position shown by the spring 87. When the trigger is released it is returned to the position shown by the trigger spring 89 and the nose turns on its pivot against its spring 82 so that it 65 can rise into the position of engagement.

In order to prevent the magazine spring 90 from raising the next cartridge too quickly a rib 91 is provided on the under side of the bolt carrier 33 which holds down the cartridge while the bolt carrier is moving rearward. When this movement is complete, the cartridge rises slightly and is then held down by a plate or frame 92 (see Figures 22 and 24) working in a slot in the right of the raceway. This frame is held 75 by a spring 93 in the position shown so that it prevents the cartridge rising until the latter is pushed forward and upward by the bolt with force sufficient to press the plate inward against the spring and the cartridge 80 then enters the chamber.

In some cases I provide the barrel with a cooling jacket 94 as shown in Figures 5, 6 and 8. In this case the barrel is not supported by the rings 6, 7 and straps 11 and 14, but the jacket is carried by a ring 95 which can turn on a horizontal pivot 96 at the front of the shoe. The muzzle is secured to the front of the jacket by a cap 97 having inwardly projecting ribs 98 which pass 90 through slots in the front of the jacket and embrace the muzzle which is made octagonal. 99 is a shield which springs over the rear of the jacket and encloses the boss and front of the sides of the weight so that 95 there is no danger of the thumb or finger being caught between the moving parts.

What I claim is:—

1. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe and a bolt carrier and bolt within the weight.

100 2. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe, and a bolt carrier and bolt within the weight, the distance through which the barrel and raceway can move relatively to the shoe bearing to the distance through which the barrel, bolt carrier and bolt can move relatively to the weight a 105 ratio that does not exceed 2:1 and is not less than unity.

110 3. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe, a bolt carrier and bolt 115

4. In an automatic fire arm, the combination of a shoe, a magazine and trigger mechanism both fast with the shoe, a raceway free to recoil upon the shoe, a barrel secured to the raceway, a weight capable of rearward movement upon the raceway, means for normally locking the weight to the shoe, means whereby the recoil of the barrel and raceway relative to the shoe releases the weight from the shoe, a bolt, means for locking the bolt to the barrel, a bolt carrier disposed within the weight and having within it helical grooves engaging helical lugs on the bolt and a spring between the bolt carrier and the weight. 70
5. In an automatic fire arm, the combination of a shoe, a magazine and trigger mechanism both fast with the shoe, a raceway free to recoil upon the shoe, a barrel secured to the raceway, a weight capable of rearward movement upon the raceway, means for normally locking the weight to the shoe, means whereby the recoil of the barrel and raceway relative to the shoe releases the weight from the shoe, a bolt, means for locking the bolt to the barrel, a bolt carrier disposed within the weight and having within it helical grooves engaging helical lugs on the bolt and a spring between the bolt carrier and the weight. 75
6. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe, a bolt carrier and bolt within the weight, a lug on the raceway projecting into a space formed in the shoe and a run-out spring contained in the space and bearing against the lug. 80
7. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe, a bolt carrier and bolt within the weight and means for preventing movement of the raceway and barrel relative to the shoe. 85
8. In an automatic fire arm, the combination of a shoe, a magazine and trigger mechanism both fast with the shoe, a barrel, a raceway secured to the barrel, the barrel and raceway being capable of recoiling upon the shoe, a weight capable of sliding on the raceway, means for normally locking the weight to the shoe, a bolt carrier and bolt within the weight, a lug on the raceway projecting into a space formed in the shoe and a run-out spring contained in the space and bearing against the lug. 90
9. In an automatic fire arm, the combination of a shoe, a magazine and trigger mechanism both fast with the shoe, a raceway, a barrel secured to the raceway, a feather on the underside of the raceway adapted to be inserted through the magazine opening in the shoe and to enter a groove therein, a weight capable of rearward movement along the raceway and means for normally locking the weight to the shoe. 95
10. In an automatic fire arm, the combination of a shoe, a magazine and trigger mechanism both fast with the shoe, a ring supported at the front of the shoe, a rod projecting forward from the ring, a second ring carried by the front end of the rod, a raceway adapted to slide upon the shoe, a barrel secured to the raceway and adapted to be supported by and to slide in the two rings, a weight capable of rearward movement on the raceway and means for normally locking the weight to the shoe. 100
11. In an automatic fire arm, the combination of a shoe, a magazine and trigger mechanism both fast with the shoe, a ring supported at the front of the shoe, a rod projecting forward from the ring, a second ring carried by the front end of the rod, a raceway adapted to slide upon the shoe, a barrel secured to the raceway and adapted to be supported by and to slide in the two rings, a lug protruding from the raceway into a cylindrical space formed in the shoe, a run-out spring located in said space and bearing against the lug, a weight capable of rearward movement on the raceway and means for normally locking the weight to the shoe. 105
12. In an automatic fire arm, the combination of a shoe, a magazine and trigger mechanism both fast with the shoe, a raceway free to recoil upon the shoe, a barrel secured to the raceway, a weight capable of rearward movement along the raceway, a horizontal transverse pivot carried by the shoe, a lever mounted on the pivot and engaging the weight and means adapted on recoil to turn the lever out of engagement with the weight. 110
13. In an automatic fire arm, the combination of a shoe, a magazine and trigger mechanism both fast with the shoe, a raceway free to recoil upon the shoe, a barrel secured to the raceway, a weight capable of rearward movement along the raceway, means for normally locking the weight to the shoe and a shield adapted to cover the rear of the barrel and the front of the weight. 115

14. In an automatic fire arm, the combination of a shoe, a magazine and trigger mechanism both fast with the shoe, a raceway free to recoil upon the shoe, a barrel secured to the raceway, a weight capable of rearward movement along the raceway, means for normally locking the weight to the shoe, a firing pin and spring carried by the weight, a sear ring adapted to engage a groove in the pin and a plunger adapted to be actuated by the trigger mechanism and to lift the ring out of the groove. 10

ARNOLD LOUIS CHEVALLIER.
